SINGLE ACTION PILE HAMMER

John J. Kupka, Gladstone, N.J., assignor, by mesne assignments, to Horn Pile & Foundation Corp., Merrick, N.Y., a corporation of New York

Filed Sept. 9, 1963, Ser. No. 307,517

5 Claims. (Cl. 173—135)

The invention herein disclosed relates to reciprocating tools of the pile hammer type.

Objects of the invention have been to provide a single acting form of hammer of simple rugged construction, free of mechanically operated valves or other critical, complicating elements, capable of withstanding hardy, rough service and adapted for manufacture at low cost.

Further special objects have been to produce this machine in an entirely closed construction adapted for submerged as well as the usual overland operations.

Other desirable objects accomplished by the invention and the novel features of construction, combination and relation of parts through which such objects are effected are set forth and will appear in the course of the following specification.

The drawings accompanying and forming part of the specification illustrate a present commercial embodiment of the invention but structure may be modified and changed as regards the immediate illustration, all within the true intent and scope of the invention as hereinafter defined and claimed.

FIG. 1 in the drawings is a vertical, sectional view of one of the hammers with the ram down on the anvil but with pressure on, lifting the differential pistons to maintain the pressure release valve at the foot of the cylinder in closed position for the upstroke of the ram.

FIG. 2 is a similar view but with the ram at the top of its stroke and the pressure relief valve open to release pressure below the descending ram.

FIG. 3 is an enlarged broken sectional view, showing the pressure release valve in the closed position.

FIG. 4 is a horizontal sectional view, substantially on the plane of line 4—4 of FIG. 1.

FIG. 5 is a horizontal sectional view on substantially the plane of line 5—5 of FIG. 1.

FIG. 6 is a horizontal sectional view on substantially the plane of line 6—6 of FIG. 1.

FIG. 7 is a side elevation of the lower cylinder taken on substantially the plane of line 7—7 of FIG. 2, with the differential valve removed.

FIG. 8 is a vertical sectional view of the lower cylinder on substantially the plane of line 8—8 of FIG. 7.

FIG. 9 is a broken vertical sectional view of the fluted portion of the ram in position establishing communication through the supply ports and flutes into the passage leading down to the expansion chamber.

FIG. 10 is a broken sectional view showing the pressure release valve in open position.

FIG. 11 is a sectional view on substantially the plane of line 11—11 of FIG. 8.

In the embodiment of the invention illustrated the ram 10 is of one-piece construction, uniform diameter, the cylinder 11 is of corresponding constant diameter and the anvil 12 has an upwardly projecting crown or piston forming portion 13, closing the lower end of the cylinder and forming with the ram and surrounding wall of the cylinder, an expansion chamber 14 beneath the lower end of the ram.

The anvil is confined to limited sliding movement in the lower end of the cylinder by links 15 and it is shown as sealed in this relation by chevron packing 16.

Motive fluid, usually steam or compressed air, is supplied to the expansion chamber 14 by a conduit 17 running down the side of the cylinder from a manifolding

2

groove or chamber 18 surrounding the ram and fed from a chest 19 on the side of the cylinder through ports 20 in the wall of the cylinder and flutes or grooves 21 in the side of the ram, which when the ram is down, as in FIG. 5 1, form by-passes communicating the cylinder ports with the manifolding groove.

The position and longitudinal extent of the flute grooves 21 in the ram thus determines admission and cutoff of motive fluid beneath the ram.

10 This control may be varied by predetermining the height of the crown on the anvil. With a higher crown the ram will be stopped sooner and at a correspondingly higher level, thus to limit admission of actuating fluid and with a lower crown the stroke of the ram will be correspondingly increased and a greater supply of motive fluid be admitted.

On its upstroke the ram uncovers an exhaust port 22 which opens to an exhaust chest 23 on the side of the cylinder, discharging through outlet 23'.

20 The drop in pressure occasioned by opening the exhaust port is utilized to effect release of pressure beneath the ram in the downstroke of the same.

This is accomplished by differential valve mechanism, shown in FIG. 3, as made up of differential pistons 24 and 25 connected by a stem 26 provided with a cam surface 27 acting on a roll 28 on the stem 29 of a pressure release valve 30 cooperative with valve seats 31 controlling passage between release ports 32 in the lower end of the cylinder and the exhaust chest 23. FIGS. 7 and 8 show these release ports 32 in communication with the exhaust chest 23.

30 This back pressure release valve is held closed by spring 33 supported by narrow bar 33' and the cam is faced to effect opening of the valve on downward movement of the differential pistons. Pressure for operating the lower, larger piston 24 is taken from the expansion chamber at the lower end of the ram by a small passage 34, leading to the lower side of that piston. Pressure for operating the upper, smaller piston 25 is taken from the lower end of the live pressure supply chest 19 by a passage 35 FIG. 4 leading from that chest to the upper side of that piston.

40 Constant live pressure is thus kept on the smaller piston but the effect of that is overcome by cylinder pressure on the larger piston, up to the time that the exhaust port 22 is opened and cylinder pressure released. When that occurs the pressure on the smaller piston snaps the pistons down and the pressure release valve 30 open and holds the valve in that state for the full downstroke of the ram.

50 To make certain that the ram will be travelled far enough up to open the exhaust port 22, pressure is bled off from the supply to the small valve piston by a passage 36, shown in FIG. 3, as extending from passage 35 to a position in front of the release valve and hence open to the cylinder by way of the release ports 32. This additional pressure applied to the ram provides the necessary boost to assure the ram uncovering the exhaust port.

55 A metering screw 37 entered in passage 36 is provided for proper adjustment of this booster effect.

60 The upper and lower ends of the ram are shown as sealed by piston rings 38, 39 and the intermediate fluted section is shown as sealed by internal, contracting rings 40 contained in a sleeve or cage 41 seated in a cavity 42 in the upper end portion of the lower cylinder section 43.

65 The upper cylinder section 44, seating in the upper end of the lower section holds this packing ring cage in place.

The anvil, sealing the lower end of the cylinder and subjected to cylinder pressure, keeps live pressure on the pile, assuring efficient hammer action.

70 With this operation it is not necessary to use cushion pads such as heretofore required, constituting at times expensive accessories.

The lower portion of the anvil projecting below the cylinder may be formed or equipped to drive different kinds of piling.

The upper portion of the anvil projecting up into the cylinder is shown as guided by a bearing ring 45, seated in the lower end of the cylinder and held by the lower cylinder head 46 which carries the anvil packing.

The upper and lower cylinder sections, with the upper cylinder head 47 and lower cylinder head 46 are held by tie rods nested in the four corners of the machine.

It is to be noted that the construction is relatively simple and of a design to be produced at reasonable cost.

The ram may be in one continuous piece, of uniform diameter and free of steps or shoulders. Similarly the cylinder bore is of the same uniform diameter with attendant manufacturing and operating advantages.

The absence of mechanically operated valves or other complicated mechanism is advantageous because of the freedom from servicing requirements and the assurance that the machine will continue in operation under adverse handling and operating conditions.

The automatically operating back pressure relief valve may be made up as a single unit bolted to the side of the cylinder with a base portion 48 sealed metal to metal to a corresponding face on the cylinder.

The passage supplying pressure to the upper smaller piston is shown as constituted in part by a groove 49 milled in the back of the base plate 48 in position to line up with the live pressure passage 35, FIGS. 3 and 4.

Operating parts of the hammer are all enclosed so that the hammer may be used for underwater operations by simply providing a hose connection from the exhaust chamber to the surface.

The compact, complete enclosure conserves heat, which is important in the operation of these machines, particularly when using the heated compressed air taken from the air compressor, disclosed in copending patent application Serial No. 294,059, filed July 10, 1963, now Patent 3,138,068 of June 23, 1964, wherein temperature of the compressed air is raised to increase power and prevent icing.

This hammer is also well designed to operate under the increased power furnished by the air compressors mentioned.

Another important feature of the invention is that no ballasting of the hammer is required for underwater operations.

To maintain constant flow area irrespective of rotary position of the ram in the cylinder, the flutes in the ram and supply ports in the cylinder bear an offset relation to each other as indicated in FIG. 5 so that any closing effect at one point is offset by reverse, opening effect at other points.

Operation

With pressure supplied to chest 19 at the inlet 50, the hammer will operate to deliver a rapid succession of blows so long as pressure is on.

With the ram at the bottom of its stroke as in FIGS. 1 and 9, motive fluid will pass from chamber 19 through flutes 21 in the side of the ram and cylinder ports 20, down through conduit 17 into expansion chamber 14 at the foot of the ram to drive the ram upward.

On the upstroke, the ram uncovers exhaust port 22, FIG. 2, releasing pressure into exhaust chamber 23 and outlet port 23'.

During upward travel pressure from the expansion chamber is on the lower larger piston 24 of the differential valve by way of passage 34 maintaining this valve in the upper position shown in FIG. 3.

At the same time live pressure from supply chest 19 is on top of the upper smaller piston 25 by way of port 35 and passages 49 and 51, FIGS. 3 and 4, but expansion chamber pressure on the larger piston maintains the valve in the upper position shown in FIG. 3 during upward travel of the ram.

When, however, the ram uncovers exhaust port 22 and thus releases expansion chamber pressure on the lower piston, the live pressure on the upper smaller piston forces the valve downward causing cam 27 to open the relief valve 31 providing escape for remaining compression chamber pressure through relief ports 32, past the valve seats 31 into exhaust chamber 23.

The pressure release valve remains open for the full downward stroke of the ram, allowing a powerful impact, but is closed at or after delivery of the blow by pressure admitted to the expansion chamber through the flutes in the ram, then registering with the ports in the cylinder.

The operation continues so long as the pressure is on and to make certain that the ram rises far enough to uncover the exhaust port, thus to continue the automatic cycling, pressure bled off from that supplied to the upper valve piston by way of passage 36, FIG. 3, and meter valve 37 is admitted over the head of the then closed release valve 30, through ports 32 into the cylinder beneath the rising ram so as to boost the ram over the exhaust port even when supplied with less than full pressure force.

What is claimed is:

1. A power hammer comprising the combination of an upright working cylinder, a ram operating in said cylinder, an anvil for operative engagement by said ram at the lower end of said cylinder, packing means sealing said ram and anvil and providing with the surrounding wall of the cylinder an annular expansion chamber at the lower end of the ram, a motive fluid supply chest on the intermediate portion of the cylinder in communication with the ram operating in the cylinder, a chamber having ports opening to the ram below said supply chest, a conduit extending from said chamber down to said expansion chamber beneath the lower end of the ram, flutes in the intermediate portion of the ram operating through said pressure supply chamber, positioned to communicate said supply chest with said ports when the ram is in position at the lower end of the cylinder, said cylinder having an exhaust port in the intermediate portion of the same positioned to be uncovered by the ram in the upstroke movement of the same, a pressure relief port in the lower portion of the cylinder for relieving pressure from the cylinder on the downstroke of the ram, and differential pressure valve means subjected to counterbalancing pressures from said expansion chamber and from said supply chest and connected to open said pressure release valve upon pressure drop in the cylinder resulting from the opening of said exhaust port in the upstroke movement of the ram.

2. The invention according to claim 1 in which there is a bleed connection extending from said supply chest to said pressure relief port ahead of said pressure relief valve for supplying "booster" pressure to assist upward travel of the ram necessary to uncover said exhaust port.

3. The invention according to claim 2 with adjustable means for varying the said pressure for "boosting" the ram to uncover the exhaust port.

4. A power hammer comprising the combination of a normally upright cylinder of substantially uniform diameter, a ram of substantially uniform diameter reciprocating in said cylinder, an anvil at the lower end of said cylinder in opposition to said ram, packing means sealing said ram and anvil in place forming with the surrounding wall of the cylinder an expansion chamber at the lower end of the ram, a motive fluid supply chest on the cylinder having an outlet port open to said ram, a feed passage having an inlet port open to the ram and

extending from said inlet port down to said expansion chamber,
said outlet and inlet ports being in separated relation one above the other,
said ram in its reciprocation travelling past said outlet 5 and inlet ports and having a recess in the side of the same of sufficient longitudinal extent to connect said ports and located to register with and connect said ports when the ram is in its lower position whereby to connect said supply chest with said feed passage 10 when the ram is substantially at the end of its down-stroke,
said cylinder having an exhaust port positioned to be uncovered by the ram in the upward travel of the ram in the cylinder,
said cylinder having a back pressure relief port in the lower portion of the same below said exhaust port and 15 means for automatically closing off said back pressure relief port on upward travel of the ram in the cylinder and for opening up said back pressure relief port on down travel of the ram in the cylinder.
5. A power hammer comprising the combination of a normally upright cylinder of substantially uniform diameter,
a ram of substantially uniform diameter reciprocating in said cylinder,
an anvil at the lower end of said cylinder in opposition to said ram,
packing means sealing said ram and anvil in place 20 forming with the surrounding wall of the cylinder an expansion chamber at the lower end of the ram,
a motive fluid supply chest on the cylinder having an outlet port open to said ram,
a feed passage having an inlet port open to the ram and 25 extending from said inlet port down to said expansion chamber,
said outlet and inlet ports being in separated relation one above the other,
said ram in its reciprocation travelling past said outlet 30 and inlet ports and having a recess in the side of the same of sufficient longitudinal extent to connect said ports and located to register with and connect said

ports when the ram is in its lower position whereby to connect said supply chest with said feed passage when the ram is substantially at the end of its down-stroke,
said cylinder having an exhaust port positioned to be uncovered by the ram in the upward travel of the ram in the cylinder,
said cylinder having a back pressure relief port in the lower portion of the same below said exhaust port, means for automatically closing off said back pressure relief port on upward travel of the ram in the cylinder and for opening up said back pressure relief port on down travel of the ram in the cylinder, including valve pistons one larger than the other and connected in opposing relation,
a valve controlling said relief port and arranged to be closed by movement of the larger valve piston in opposition to the smaller piston and to be opened by movement of the smaller piston in opposition to the larger piston,
a constant pressure connection from the supply chest to the smaller piston, and
a variable pressure connection from the expansion chamber to the larger piston,
whereby pressure from the expansion chamber will have the effect of holding the pressure relief valve closed during upward travel of the ram and pressure on the smaller piston will be effective to open the relief valve after the ram in its upward travel has opened the exhaust port.
